UNITED STATES PATENT OFFICE.

FRANK F. MILLER, OF YANKTON, SOUTH DAKOTA, ASSIGNOR TO ELMER HICKS, OF YANKTON, SOUTH DAKOTA.

RUBBING-POST.

1,243,961.

Specification of Letters Patent. Patented Oct. 23, 1917.

Application filed July 13, 1915. Serial No. 39,607.

To all whom it may concern:

Be it known that I, FRANK F. MILLER, a citizen of the United States, residing at Yankton, in the county of Yankton and 5 State of South Dakota, have invented certain new and useful Improvements in Rubbing-Posts, of which the following is a specification.

This invention relates to rubbing posts for 10 use in animal husbandry, and is designed more particularly for supplying oil or disinfectants to hogs and small stock.

One object of the invention is to effect an economy in the use of the oil or other liquid 15 and to permit a limited discharge of the same when an animal rubs against the actuating lever or rubbing bar.

A further object of the invention is to prevent discharge of the liquid except when the 20 rubbing bar is actuated, and a further object of the invention is to protect the supply of liquid from contamination.

A further object of the invention is to provide means whereby the quantity discharged 25 at any one time may be regulated, and a still further object is to provide means whereby the rubbing bar will be permitted to swing freely at all times but will be limited in its movement and will not be liable 30 to choke with mud.

Other incidental objects of the invention will appear as the description proceeds, and the invention resides in certain novel features which will be particularly pointed out 35 in the claims following the description.

In the drawings:—

Figure 1 is a front elevation of a rubbing post embodying my improvements;

Fig. 2 is a side elevation of the same;

40 Fig. 3 is a vertical section taken longitudinally of the trough;

Fig. 4 is a detail perspective view of the trough, the upper end of the rubbing bar and the keeper or bracket by which the rubbing bar is maintained in its position relative to the trough, these parts being shown detached but approximately in their proper relative positions;

50 Fig. 5 is a similar view of the lower end of the rubbing bar, the stop by which the movement of the bar is limited; and the bracket or keeper at the lower end of the post.

In carrying out my invention, I employ a 55 base board or post 1 which may be of any

desired dimensions and may be secured to the side of a building, a fence post, a tree or other object located where it will be accessible to the animals. At an intermediate point of the height of this post or base 60 board, I secure a trough 2 which is preferably a casting having lateral lugs 3 at one end which are provided with openings or notches 4 whereby fastening bolts 5 may be inserted through the lugs and the base board 65 or post 1 to secure the trough rigidly in place. The outer end of the casting presents a circular wall 6 whereby a well is formed to contain a supply of liquid. At the center of this well is a small lug or projection 7, the purpose of which will presently appear.

The circular wall 6 is connected with the lugs 3 by parallel side walls 8, and between the said side walls extends a rear wall or web 9. The bottom of the trough is raised adjacent the rear wall 9, as shown most clearly at 10 in Fig. 3, and through the said raised portion 10 is provided a passage or opening 11 through which the liquid may 75 flow to the rubbing bar. From the bottom of the trough, in advance of the raised portion 10, rises a pin 12 which is adapted to enter the container 13 through the spout 14 thereof and thereby lift the ball valve 15 80 85 so as to permit flow through the said spout.

It will be understood that, when this container is being filled, the ball valve 15 will drop to the bottom of the same and leave the inlet or spout unobstructed. When the 90 container is inverted, the ball will drop to and fit closely against the inner end of the spout and seal the same so as to prevent the escape of the liquid and, when the container is fitted over the pin 12, the valve will be 95 moved from the spout by the upper end of the pin sufficiently to permit the liquid to flow into the trough, as will be readily understood on reference to Fig. 3. It will also be understood that, while inverting the container, the end of the spout will be covered by the thumb or in any convenient manner to prevent loss of liquid.

Secured to the base board or post 1, immediately above the trough and in position 105 to rest upon the upper edges of the walls thereof, is a keeper or cover 16 having an upstanding lug 17 at its rear end through an opening 18 in which is inserted a bolt 19 to secure the said lug firmly to the base 110

board. This keeper is provided adjacent its front end with an opening 20 which receives the spout 14 of the container and thereby serves to guide the spout to its proper position and also aids in maintaining the container in place. Between its ends, this keeper or cover is provided with a transverse rib 21 having a groove 22 in its under side which receives a pin or bolt 23 which is inserted through the arms 24 at the upper end of the rubbing bar to pivotally support the said bar upon the trough, as shown in Fig. 3. The pivot 23, it will be noted, is located practically in the same vertical plane as the opening 11 so that the upper end 25 of the rubbing bar will be directly under the said opening. This upper end of the rubbing bar is convex so that the oil dropping thereon will be directed onto the front surface of the rubbing bar and upon the said front surface is provided a series of downwardly inclined ribs or baffles 26 which extend alternately from the opposite sides or edges of the bar, whereby the oil will be caused to flow tortuously over the surface of the bar and will, consequently, be retarded in its passage to the lower end of the bar. The arms 24, which rise from the rubbing bar and pivotally support the same, are provided with eyes or perforated lugs 27 at their upper ends which are adapted to receive a presser rod or arm 28 which is preferably in the form of a rod projecting forwardly from the upper end of the rubbing bar past the container and having its front end turned inwardly, as shown at 29, and then downwardly, as shown at 30, to bear upon the upper side of a plunger or cup piston 31. This plunger or piston 31 plays in the well 6 and is supported freely therein by a coiled spring 32 which is disposed between the upper end of the plunger and the bottom of the well and has its lower end fitting around the stud or lug 7 so as to be retained in its operative position.

It will be readily understood from the foregoing description, taken in connection with the accompanying drawings, that, when an animal rubs against the rubbing bar, indicated as a whole by the reference numeral 33, the said bar will be caused to swing about its pivot 23 so as to approach parallelism with the base board 1, the result being that the presser arm 28 will be moved downwardly and will depress the plunger 31 against the tension of the spring 32 and thereby eject a small quantity of the oil from the well. The ejected oil will rise over the raised portion 10 of the trough and escape through the opening 11 onto the convex surface 25 of the rubbing bar, whence it will be passed over the front face of the said bar, as previously described. The spout 14 is to be of such length that

the lower end thereof will lie just below the upper surface of the raised portion 10 of the trough. Consequently, the oil from the container 13 will flow into the trough until it rises to the level of the lower end of the spout and will seal the same so that further flow will be arrested. When the plunger is depressed, its lower end will enter the liquid and the pressure exerted by the plunger will cause the liquid to rise over the raised portion 10 and escape. As long as the animal presses against the rubbing bar, the plunger will be held depressed and, consequently, but one discharge of the liquid will be made. As the plunger or piston has an open bottom but closed top and sides, an air cushion will be formed under the same to prevent it being moved violently so as to splash the liquid and, consequently only a small quantity of the liquid will be discharged. When the parts return to their normal positions, upon the animal leaving the rubbing bar, the piston will serve to some extent as a pump to suck an additional supply of liquid from the container. It will be readily understood that the presser arm 28 may be disposed at either side of the rubbing bar and may be set to vary the stroke of the plunger by adjusting the nuts 34 which secure the arm in the upper end of the rubbing bar.

The lower end of the rubbing bar is provided with a depending lug 35 to which is pivoted the upper end of a detent or curved block 36 having lateral pins or stops 37 at its lower end. This block 36 is inserted upwardly through a slot 38 in the top plate of a bracket 39 which is secured to the lower end of the base board 1 and plays freely in the said slot. When the rubbing bar is in the position shown in Fig. 2, the pins 37 will contact with the under side of the top branch of the bracket 39 and will thereby limit the outward movement of the bar. When an animal rubs against the bar, the block 36 will move downwardly through the slot 38 and will thereby prevent lateral movement of the rubbing bar, as will be readily understood. As this bar will be in movement almost constantly, it will be readily understood that mud cannot collect in the slot 38 so as to clog the action of the device.

The container is supported upon the cover 16 by a bail 40 which is secured to the end of the container and is so disposed as to fit around the spout 14 and provide a foot 41 adapted to rest upon the cover 16, as shown most clearly in Fig. 2. The spout is thus relieved of the weight of the can and is also guarded against bending or breakage. The upper end of the container is held to the base board by a bail or keeper 42 passed around the container and having its ends engaged in eyes or rings 43 on the base

board. The base board is preferably of wood so as to reduce the weight for shipping purposes. Moreover, when the parts are clamped against a wooden base board, the 5 lugs will be partly embedded in the board so as to hold firmly, whereas, if they were clamped against a smooth metal post, they would work loose through use and the working parts would get out of alinement. The 10 notches in the several lugs provide for accurate alinement in setting up the device.

It is thought to be clear from the foregoing description that I have provided an exceedingly simple device which may be 15 readily set up at any desired place and by the use of which the disinfectant, insecticide or other liquid may be economically supplied to the animals.

Having thus described the invention, what 20 is claimed as new is:

1. In an apparatus for the purpose set forth, the combination of a trough, a well therein, a hollow piston mounted in the well, and having an open bottom and closed sides 25 and top, means for holding the piston normally raised, a rubbing bar mounted to swing adjacent the trough, and means carried by the rubbing bar for depressing said piston.

2. In an apparatus for the purpose set forth, the combination of a trough having an outlet through its bottom, a rubbing bar having a receiving surface disposed below said outlet and provided with arms extending 35 above the trough, a pivot bolt inserted through said arms and resting on the trough, a keeper resting upon the trough and extending over said pivot bolt, means for supplying liquid to the trough, and means controlled by the rubbing bar for forcing a portion of the liquid through said outlet.

3. In an apparatus for the purpose set forth, the combination of a trough having an outlet through its bottom, a rubbing bar 45 having a receiving surface disposed below said outlet, a pivotal support for the rubbing bar extending over the trough, a keeper resting on the trough and having a groove receiving said pivotal support and provided 50 with an opening in advance of said groove, a container provided with a spout passing downwardly through said opening and terminating below the upper end of the outlet in the trough, and means controlled by the 55 rubbing bar for feeding a portion of the liquid in the trough through said outlet onto the rubbing bar.

4. In an apparatus for the purpose set forth, the combination of a trough having a

well at one end, a cover extending over the 60 trough between the well and the opposite end thereof, a hollow floating piston mounted in the well and having an open bottom and a closed top and sides, a rubbing bar pivotally mounted adjacent the trough, and a 65 presser arm carried by said rubbing bar and bearing upon said piston.

5. In an apparatus for the purpose set forth, the combination of a trough having an outlet at one end and a well at the other 70 end, a rubbing bar pivotally hung adjacent the trough, a hollow piston mounted in said well and having an open bottom and closed top and sides, means for holding the piston normally elevated, and a presser arm secured 75 at one end to and adjustable through the upper end of the rubbing bar and bearing at its free end upon said piston.

6. In an apparatus for the purpose set forth, the combination of a base board, a 80 trough secured thereto and projecting laterally therefrom, a bracket secured to and projecting from the base board below the trough, said bracket being provided with a slot in its upper portion, a rubbing bar pivotally hung upon the trough, means controlled by the rubbing bar for forcing liquid from the trough onto the bar, a detent inserted upwardly through the slot in the said bracket and having its upper end pivoted 85 to the lower end of the rubbing bar, and stops on the sides of said detent adapted to impinge against the upper portion of the bracket.

7. In an apparatus for the purpose set 90 forth, the combination of a trough, a cover for the same, a rubbing bar pivotally mounted adjacent the trough, a container adapted to supply liquid to the trough, a bail secured to said container and resting upon said cover 100 to support the container, and means controlled by the rubbing bar to force liquid from the trough.

8. In an apparatus for the purpose set forth, the combination of a trough having 105 a well and an outlet spaced from the well, a rubbing bar pivotally mounted adjacent the trough to swing below and across the vertical plane of the outlet, a plunger mounted in the well, means for holding the plunger normally elevated, and a pressing arm extending from the rubbing bar and bearing upon the plunger to depress the same and effect a discharge from the trough when the rubbing bar is actuated.

In testimony whereof I affix my signature.

FRANK F. MILLER. [L. S.]
